UNITED STATES PATENT OFFICE.

JAMES ERICKSON, OF HOLMESBURG, PENNSYLVANIA.

BALLAST-TREATING MACHINE.

Application filed August 17, 1926. Serial No. 129,693.

It is necessary that the stone ballast of railway tracks be treated at intervals for the purpose of removing from the voids between the stones constituting the ballast material dirt and similar material which tends to clog the layer of ballast and prevent the free drainage of water therethrough.

The means heretofore employed for the purpose of treating the ballast has been unsatisfactory because of the slowness with which the treatment may be effected.

The ballast treating means of the present invention is adapted for treating the ballast upon the sides of railway tracks and between adjoining tracks and for redepositing the treated and cleaned ballast after treatment.

The general object of the present invention is to provide ballast treating means which is adapted to be mounted upon the body of a railway car and, when operated, to deposit the dirt and other clogging material in the said body and simultaneously to deposit the cleaned rock constituting the ballast at the sides of railway tracks and between adjoining tracks should there be two tracks in adjoining relation to each other.

It also is an object of the invention to provide a jiggling pan onto which the material to be treated may be deposited and means for effecting operation of the said jiggling means to cause separation of the ballast rock from the dirt and other impurities or clogging material which may be present and intermingled therein.

Another object of the invention is to provide means whereby the ballast after treatment may be deposited automatically in positions in rear of the positions from which the said ballast was removed, in order that the gathering and depositing of the untreated ballast material onto the jiggling pan of the ballast treating means may be carried on simultaneously with the depositing of the treated ballast in place upon the track bed.

To these and other ends my invention comprehends the construction and arrangement of parts as hereinafter described in detail, particularly pointed out in the claims and as illustrated in the drawings in which I have illustrated one form of a convenient embodiment of apparatus or means embodying the invention.

However, it will be understood that the invention is susceptible of embodiment in

other forms of construction than that shown and that changes in the details of construction may be made within the scope of the claims without departing from the principle 60 of the invention.

In the drawings:

Fig. 1 is a view in longitudinal section of an apparatus or means embodying the invention and in transverse section of a car 65 body upon which the said apparatus or means is adjustably mounted, the said figure also showing a wheel and a portion of the axle for supporting the said car body and also, in section, one rail of a railway 70 track and a portion of a cross-tie upon which the same is supported;

Fig. 2 is a view in side elevation of the apparatus or means embodying the invention and also showing the upper portions of 75 the opposite sides of the railway car body upon which the said apparatus or means is supported;

Fig. 3 is a view in top plan of the means embodying my invention, a portion thereof 80 being broken away in order to show the details of construction of a part of the mechanism thereof, and also showing a portion of the supporting car body in top plan;

Fig. 4 is a view in end elevation of the 85 ballast treating machine, a portion of an element thereof being broken away, the said view also showing a portion of a railway car and track in side elevation; and

Fig. 5 is a view in transverse section of 90 a portion of the said machine taken on the line 5—5 of Fig. 1, the said view also showing a portion of the inside of one side of the car body upon which the machine is supported.

Referring to the drawings, 1 designates a railway track and 2 a railway car mounted upon wheels which are supported upon the rails of the said track.

Although not shown, it will be understood 100 that not only between the cross-ties of the track, but also upon both sides of the track and in between adjoining tracks there is present a quantity of ballast consisting of broken stone of usual size and quality. This 105 ballast or stone, as already indicated, in the course of time becomes filled with dirt and other foreign matter, whereby the interstices or voids between the stones become filled, so that the ballast does not satisfactorily 110 perform its function of draining off the water in case of rain. Hence, it becomes nec-

5 essary at intervals to treat the ballast for the purpose of removing therefrom such dirt and other foreign materials. To that end the machine which will now be described in detail has been provided.

10 The machine comprises a frame structure consisting of base side members 3 which are joined at their opposite ends by means of connecting and bracing members 4, 5 and 6. The members 4 and 5 consist of channels while the member 6 is shown as consisting of a cylindrical rod or bar, but it may consist of a member of any other suitable shape in cross-section. Standards 10 are connected with the base members 3 at the opposite sides of the base frame of the machine near the front end thereof. These standards extend upwardly, as shown. The upper portions of these standards are provided with 20 strengthening plates 11. The said standards are connected by means of a bar 12 which extends therethrough and also through the stiffening plates 11. Side frame members 15 of channel shape are connected at their upper front ends to the standards 10. The cross connecting bar 12 extends through the said members 15 near their upper front ends, as shown. The opposite ends of the said side members 15 at the discharge or 25 rear end of the machine are connected to the adjoining ends of the base frame members 3 by means of rivets, as indicated at 16. Relatively short standards 17 are secured to the side frame members 3 near the discharge 30 or rear end of the machine, which standards are also connected with the inclined side frame members 15. The members 3, 10, 15 and 17 are tied rigidly together so as to form a strong, rigid frame structure. The 35 top edges of the opposite sides of the car body are provided with wear plates 21 and 22 which may be of any preferred shape in transverse section. In the drawings I have shown the wear plate 21 as of channel shape, while the wear plate 22 is of angle shape.

40 It is apparent that the frame structure may be moved to different positions with respect to the length of the car body merely by sliding the same upon or over the wear plates 21 and 22. If preferred or desired anti-friction means may be provided for facilitating the movement of the frame structure with the operative parts of the machine thereon to different positions upon the car body.

45 The standards or projections 10 and 17, previously referred to, project above the upper edges of the inclined side frame members 15 for a purpose which will be herein-after described.

50 Supported upon the frame structure is a jig pan 25 having a perforated bottom 26, as shown. The perforations should be of a size sufficient to permit the passage there-through of the dirt and other material which

it is desired to remove from the ballast stone, but such perforations must be smaller than the diameter of the smallest portions of stone which it is desired to retain in the ballast mass.

70

The jig pan 25 is mounted upon parallel links 28 located at the opposite sides of the frame structure of the machine. The lower ends of the front links of the respective pairs of parallel links 28 are pivotally supported upon the lower ends of brackets 29 which are secured to and depend from the opposite inclined frame member 15. The lower ends of the rear links of the respective pairs of parallel links are pivotally connected to the side members 3 of the base of the frame structure, as indicated at 30. The upper ends of the links are pivotally connected to the opposite sides of the jig pan, as indicated at 31.

75

80 For the purpose of effecting oscillating or jiggling movements of the jig pan 25 I have provided connecting links 35, the upper ends of which are connected to the opposite sides of the jig pan, while the lower ends thereof are connected with eccentrics 36 mounted upon a shaft 37 supported in bearings 38 provided upon standards 10. The said shaft is provided with a wheel 38^a which is adapted to be driven by means of a suitable belt 39 which is in turn driven by means of a small wheel 40 mounted upon the shaft 41 of an engine indicated at 42. A fly-wheel 43 is also mounted upon the said shaft 41. The engine structure is mounted upon a platform 45 which is secured to the upper edges of the cross-beams 4 and 5, previously referred to.

85

90 The engine structure is merely indicated in outline because any suitable construction of engine may be employed for the purpose of driving the wheel 38^a and the shaft 37 on which it is mounted to effect reciprocation of the connecting rods 35 to thereby cause oscillating or jiggling movements of the jig pan 25.

95

95 In its oscillating movements the jig pan 25 is steadied and guided by the upper end portions of the standards 10 and 17 which project above and beyond the upper edges 100 of the inclined side members 15 of the frame structure of the machine.

105

110 For the purpose of decreasing the shock, in case the oscillating jig pan should strike the inclined side members 15 of the structure, I have provided buffer blocks 50 of rubber or other suitable material.

115

120 For the purpose of protecting as far as may be practicable the engine and associated parts of the structure from dust and dirt I have provided a protecting hood 51 which is mounted upon the upper end portion of the jig pan 25. This hood extends forwardly over and above the top of the engine structure and its sides are closed so as to partially 125

130

inclose the upper portion of the engine structure. As a further protecting means I have also provided a hood 52 mounted at its lower edge upon the base frame members 3 and extending crosswise of the machine and around and over the wheel 38^a and shaft 37. The upper edge of the protecting hood 52 terminates in adjacent relation to a cross-beam 53 which extends between and connects the inclined side members 15 of the frame structure. The protecting hoods 51 and 52 are preferably constructed of sheet metal, as shown.

At its discharge end the machine is provided with a chute 60 through which the cleaned ballast material is redeposited upon the track bed. The chute comprises inner and outer walls 61 and 62, and edge walls 63 and 64. The top edge of the inner wall 61 terminates in a plane substantially flush with that of the adjoining edge of the bottom 26 of the jig pan 25 when the latter occupies its lowermost position. The outer wall 62 and the opposite edge walls 63 and 64 of the chute extend upwardly above the top edge of the inner wall 61. The distance between the extended portions of the edge walls 63 and 64 is slightly greater than the exterior width of the jig pan 25, so that in the oscillations of the latter it will not strike the said edge walls.

The lower edges of the inner and outer walls 61 and 62 and the edge wall 64 extend transversely of and are inclined with respect to the jig structure, as indicated at 65, so that the discharge opening 66 of the chute is located adjacent the lower end of the edge wall 63. The purpose of so locating the discharge opening of the chute will be fully set forth hereinafter.

The wall 64 is provided with an eye 67 which is adapted to be mounted upon a supporting pivot 68 which is secured to one of the side members 15 of the frame of the machine by means of rivets 70. The eye 67 is retained upon the pivot 68 by means of a pin 71. An anchoring and supporting chain 75 is secured to the opposite edge wall 63 of the machine near the lower end thereof and is adapted to engage with hooks 76 located at intervals upon the adjoining side of the car body.

When the railway car upon which the machine is mounted is stationary and the said machine is in use the chain 75 is connected with a hook 76 in a way to support the chute in depending position to discharge the treated ballast onto the track bed, as shown in Fig. 4. When, however, it is desired to transfer the car upon which the machine is mounted to some other location upon the railway track the lower end of the chute is lifted by turning the said chute about its pivot 68 and is supported in such elevated position by engaging a hook 76 with a link

of the chain 75 located more nearly to the point of connection of the chain to the chute.

In the use of the machine it will be assumed that it is located adjacent or near one end of a car body and that as the work proceeds it will be moved forward in the direction of the arrow 78 in Fig. 4. The wall 64, therefore, may be regarded as a forward edge wall and the wall 63 as a rear edge wall.

The material to be treated may be scooped up by dredge buckets from positions or locations corresponding to the forward part of the chute or beyond such forward part and deposited upon the upper end portion of the machine adjacent the hood 51. If at such time the jig pan is being oscillated the material will flow downwardly upon the bottom of the jig pan; the dirt and other impurities will pass through the openings therein and be deposited in the car body, while the cleansed stone will be discharged into the chute and be deposited through the opening 66 at points in rear of that from which the untreated ballast was previously obtained and placed upon the jig pan for treatment. As the work proceeds the car with the machine thereon may be moved forward in order to bring the latter into operative relation to the ballast to be treated; also, as the portion of the body underneath the jig pan becomes filled with the dirt and other impurities which are sifted through the holes or perforations in the bottom of the jig pan the machine is moved forward upon the top edges of the car body so as to deposit the dirt and other impurities in an unfilled portion of the car body.

Any suitable means may be provided for scooping up the uncleared ballast and depositing it in the jig pan, but I prefer to employ dredge buckets of usual construction and mounted and operated in the usual manner for that purpose.

It will be seen that by my invention I am enabled to provide a machine which is well adapted for the economic treatment of the ballast of railway tracks for the purpose of removing dirt and other impurities therefrom and for depositing the cleaned ballast directly from the machine onto the track bed at points in rear of that from which it was taken to be placed upon the jig pan of the machine.

Having thus described my invention, what I claim and desire to secure by Letters Patent is:

1. In a railway ballast treating machine which is adapted to be movably mounted upon a railway car body, the combination of a frame mounted upon the said car body, a jig pan having a perforated bottom supported upon said frame, said jig pan being angularly related to a horizontal plane, power means for effecting oscillations of the

said jig pan, a chute supported to swing in a plane which extends transversely of the said jig pan, the upper end of said chute being open and being located in cooperative relation to the lower end of the said jig pan, means for supporting said chute thereon in depending vertical or in elevated position in adjoining and parallel relation to a side of the said car body, and the said chute being adapted to deposit the cleaned ballast in positions in rear of the front edge portion of the said machine.

2. In a railway ballast treating machine, the combination of a frame structure adapted to be mounted upon a railway car body and to be moved from end to end thereof, a jig pan having a perforated bottom mounted upon the said frame structure, means for effecting oscillatory movements of the said jig pan, a pivot bar mounted upon said

frame structure at a point adjoining the discharge end of the said jig pan, the said pivot projecting laterally of and beyond the adjoining side of the said railway car, a discharge chute having an open upper end which is adapted to be located in operative relation to the discharge end of the said jig pan to receive treated ballast therefrom, the forward edge wall of said chute being pivotally supported upon the said pivot bar, whereby the said chute may be swung into adjusted positions in a plane extending at right angles to a horizontal plane, and means for supporting the said chute in adjusted angular positions.

In testimony that I claim the foregoing as my invention, I have hereunto signed my name this 13th day of August, A. D. 1926.

JAMES ERICKSON.
